UNITED STATES PATENT OFFICE

FRANK J. SCHLEICHER, OF UNIVERSITY CITY, MISSOURI

BOX

Application filed May 29, 1929. Serial No. 366,813.

This invention relates to boxes made of cardboard or-like material and has special reference to boxes having the appearance in plan view of two hearts placed in overlapping relationship so that one lobe of each heart is overlapped by one lobe of the other.

An object of the invention is to provide an improved box of the type mentioned wherein in the side wall is composed of a single strip 10 of a length equal to the distance around the edge of the double heart-shaped sheet so that when said strip is placed about said sheet the ends of the strip will be in adjacent or abutting contact; and to provide in said 15 strip defined lines for bending said strip in the sharp corners of the double heart-shaped sheet and about a sharp point so that the ends of all of said strips are necessarily and essentially brought together at a predetermined point along the edges of all of said 20 sheets. In this way the assembly of the box elements is greatly expedited and facilitated and the cost of manufacture is largely reduced and the output correspondingly increased because of the novel construction and 25 relationship of said parts. That is to say, by my improved construction the ends will be brought together at the same predetermined points on all double heart-shaped 30 sheets automatically and as an incident to the bending of said strip into any of said corners or about said sharp point without the necessity of first placing and securing either one of the ends in connection with said 35 double heart-shaped sheet. I have found by practice that these desirable and advantageous results are obtained and I have known by experience that said results have been desired and sought; and so far as I am informed 40 my present invention is the only solution that has thus far been devised.

Other objects and advantages of the invention than those specifically mentioned will appear from the following description, reference being made to the accompanying drawing in which

Fig. 1 is a detail plan view of the rectangular strip from which the box side wall is formed.

Fig. 2 is a view looking toward one edge of

said strip and showing the transverse score lines which are formed at predetermined intervals on said strip.

Fig. 3 is an end view of said strip showing the longitudinal score line. 55

Fig. 4 is a view showing the manner in which the strip forming the side wall is attached to the double heart-shaped top or bottom section of the box.

Fig. 5 is a side elevation of the box. 60

Fig. 6 is an enlarged sectional view on the line 6—6 of Fig. 4 showing the box proper and the lid therefor in assembled relationship.

This present application is a continuation, 65 in part, of application Serial No. 246,543, filed January 13, 1928.

In the embodiment of the invention shown the box base consists of two sheets 1 and 2, each having a double heart-shaped contour 70 or form; that is to say, each of said sheets has two side lobes 3 and a central portion 4. The edges of the side lobes 3 curve to intersection with the edge of the central portion 4 to form notches having sharp corners 5 in one edge of the sheet 1. The opposite edge of the sheet comprises two sharp corners 5 so that the sharp points 6 are spaced apart the same distance as are the sharp corners 5. Between the sharp points 6 a notch is formed 75 having a sharp corner 7 which is midway between the sharp points 6 and therefore on the extended radius of the curved edge of the part 4 of the sheet 1. The outer base sheet 2 of my improved box is somewhat 80 larger than the inner base sheet 1 and is of slightly different shape so that when the box is completed the outer base sheet 2 projects outwardly beyond the side wall of the box and guards and shields the joint of the side 85 wall with the bottom wall and has two sharp corners 8 directly or nearly in alignment with the corners 5. That is to say, the corners 8 are spaced apart the same distance as are the corners 5. The outer base sheet 1 also has 90 two sharp points 9 directly or nearly opposite the sharp points 6. The sharp corners 8 and 5 at one edge of the base sheet 1 are in a straight line with the sharp points 6 and 9 at the opposite edge of said base sheet. 95

100

Thus there are two straight lines of sharp corners and sharp points, each line including a corner 8, a corner 5, a point 6, and a point 9. And these two straight lines are parallel. The outer base sheet also has a sharp corner 10 in alinement with the sharp corner 7 of the base sheet 1.

The box side wall 11 is preferably formed from a single rectangular strip, one edge of which is cut to form a plurality of tongues 12. The length of this strip is the same or approximately the same as the distance around the edge of the base sheet 1 so that when said strip is bent around the base sheet 1 and into contact with the entire peripheral edge thereof the ends of the strip will of necessity and as a necessary consequence of such arrangement be brought into abutting contact or approximately so. The strip 11 is formed with a longitudinal score line 13 parallel with and adjacent to one edge of said strip and said edge is cut inwardly to said score line 13 to form the tongues 12. These tongues may be bent along the score line 13 and at right angles to the body of the strip, as clearly shown in Figs. 4 and 6, and extended and secured to the under side of the base sheet 1. The attachment of the tongues 12 to the base 1 may be by means of a quantity of glue 14 placed along the marginal portion of the base sheet 1 against which the tongues 12 are to be fastened. The body of the strip 11 is bent to follow the contour of the base sheet 1 and the tongues are engaged and fastened by the glue 14. As clearly shown in Figs. 1 and 2, a transverse score line 15 is formed entirely across the inner side of the strip 11 from the score line 13 to the opposite edge of said strip. And this score line 15 is essentially located so that it does not extend from any one of the tongues 12 but is in continuation of one of the cuts or notches 16 between two adjacent tongues 12. In the embodiment shown this score line 15 provides a defined terminal portion 17 of the strip 11 which is equal to the distance from the sharp point 6 to the sharp corner 7 of the base sheet 1. The base sheet 1 is formed with an outer transverse score line 18 spaced from the score line 15 a distance exactly equal to the distance from the sharp corner 7 to the other sharp point 6 of the base sheet 1 so as to provide a defined part 19 of the strip 11 between the score lines 15 and 18 exactly equal to the distance from the sharp corner 7 to the sharp point 6. Thus, the two defined portions 17 and 19 of the strip 11 will fold against the edges of the base sheet 1 between the sharp points 6, while the strip 11 will bend outwardly along the score line 15 so as to seat closely into the sharp corner 7, the two defined portions 17 and 19 diverging from each other along the diverging edges of the base sheet 1 from the sharp corner 7 to the sharp points

6. Essentially the score line 18 does not intersect any one of the tongues 12 but said score line is essentially in continuation of one of the cuts or notches 20 separating two adjacent ones of said tongues 12. The cut or notch 20 is necessarily of such width that the two tongues 12 separated thereby will not overlap when the side wall 11 is bent about the sharp point 6. The wall strip 11 is also formed with two transverse score lines 21 and 22 extending from the score line 13 in continuation of two cuts or notches 23 and 24. It is essential that these score lines 21 and 22 do not intersect any of the tongues 12 and it is equally essential that said score lines be in continuation of notches or cuts 23 and 24 separating adjacent ones of the tongues 12 so as to permit the wall 11 to bend sharply along said score lines 21 and 22 which constitute designations for placement opposite the sharp corners 5. It is essential that the distance from the score line 18 to the score line 21 be equal to the distance around the edge of the base sheet 1 from the sharp point 6 to the nearest sharp corner 5; and that the distance from the score line 21 to the score line 22 be equal to the distance around the edge of the base sheet 1 from the sharp corner 5 at which the score line 21 is located to the other sharp corner 5; and that the distance from the score line 22 to the end of the strip 11 be equal to the distance from the sharp corner 5 at which said score line 22 is located around the edge of the base sheet 1 to approximate abutting contact with the opposite end of the strip 11 which, as herein shown, is at one of the sharp points 6. In this arrangement the two tongues 12 at the ends of the strip 11 and which are designated by 12^a in Fig. 4, do not overlap but have their adjacent edges diverging or inclined so that both tongues may be engaged by the glue 14 and thus securely attach the ends of the strip 11 to the base sheet 1. In this assembly of the device a strip 25 of flexible material is extended across the point between the ends of the wall 11 and attached to the outer side of said wall. Thus, as will readily be seen by reference to Fig. 2, any outward strain or pressure exerted or applied against the inner side of the wall adjacent to either end thereof exerts a longitudinal pull upon that portion of the strip 25 which is attached to the other end of the wall 11 so that considerable resistance to tearing is obtained.

After the box wall has been attached to the base sheet 1 in the manner described the base sheet 2 is attached to the tongues 12 by glue or the like in the relationship hereinbefore described. For this purpose a strip of glue is applied to the surface of the sheet 2. This strip of glue is spaced inwardly from the edge of said sheet and is continuous, having the shape or outline of the strip of glue 14

in order firmly to engage the tongues 12, but not to extend outwardly beyond said tongues.

By reference to Fig. 4 it will be seen that the assembly of the box elements having the strip 11 formed and constructed as shown and described is greatly expedited and facilitated so that the cost of manufacture is largely reduced and the output correspondingly increased and that these desirable results are obtained because of the essential elements of the invention shown and described. The score lines 21 and 22 constitute demarcations or indicia for placement of the wall 11 in proper position about and against the base sheet 1. For, these score lines 21 and 22 must be opposite or at the sharp corners 5, the intermediate portion of the wall 11 being curved against the intermediate curved portion of the base sheet 1. The remaining 10 portions of the wall 11 are curved and folded about the edges of the base sheet 1, the score line 18 essentially being located about one of the sharp points 6 and the score line 15 essentially being located at the sharp corner 25 7. Or the bending of the strip 11 about the sharp point 6 and also the bending along the score line 15 at the sharp corner 7 essentially results in proper location of the score lines 21 and 22 at or opposite the sharp corners 5.

I have described the structure of the box proper and it will be understood that the lid structure will be the same and Figs. 5 and 6 illustrate the box and lid assembled with each other. The parts previously referred to are practically duplicated in the lid and are numbered 1^a, 2^a, 3^a, etc., in order to correspond to the parts of the box having the numbers 1, 2, 3, etc.

It will be seen that the outer base sheet 1 is attached to the tongues 12 by fastening means such as glue independently of the fastening means by which the tongues 12 of the wall 11 are attached to the inner base sheet

2. Accordingly, by making the base sheets and the wall out of appropriately coated cardboard I am enabled to dispense with the use of cover sheets or the like, leaving the outer edge 26 of the base sheet 2 cut or un-covered. This I have designated a cut edge base. This construction may be the same in the lid or varied as desired. The elements of this box may be assembled by a box-making machine of the type used for assembling 55 rectangular boxes, modified so that the machine would handle the double heart-shaped contours herein shown.

The invention may be varied within equivalent limits without departure from the nature and principle thereof. I do not restrict myself unessentially, but what I claim and desire to secure by Letters Patent is:—

1. A box comprising a bottom wall having in one edge two notches each formed with a sharp inner corner and having on their op-

posite edges two sharp points and having between said sharp points a notch provided with a sharp corner, in combination with a wall-forming strip having two defined parts located against the edges of said bottom wall from said last-named sharp corner to said sharp points respectively, and having at its outer side a score line opposite one of said sharp points, said strip being bent transversely across said score line and around the marginal edge of said bottom wall and sharply into both of said sharp corners of said first named notches; and having two transverse score lines opposite said sharp corners of said first named notches and along which two score lines said strip is bent transversely and sharply into said sharp corners of said first named notches; tongues projecting from said strip in a relationship to said score lines in which the spaces separating said tongues are opposite the ends of said score lines; and means securing said tongues to one of the surfaces of said bottom wall.

2. A box comprising a bottom wall having in one edge two notches each formed with a sharp inner corner and having on their opposite edges two sharp points and having between said sharp points a notch provided with a sharp corner, in combination with a wall-forming strip having two defined parts located against the edges of said bottom wall from said last-named sharp corner to said sharp points respectively, and having at its outer side a score line opposite one of said sharp points, said strip being bent transversely across said score line and around the marginal edge of said bottom wall and sharply into both of said sharp corners of said first named notches; and having two transverse score lines opposite said sharp corners of said first named notches and along which said two score lines said strip is bent transversely and sharply into said sharp corners of said first named notches, said strip also having a longitudinal score line; tongues projecting from said strip along said longitudinal score line in a relationship to said score lines in which the spaces separating said tongues are opposite the ends of said score lines; means securing said tongues to one of the surfaces of said bottom wall; and an outer wall having sharp corner notches in one edge and sharp points on the opposite edge and secured to said tongues in a relationship in which said sharp corners are in straight alinement with each other and with the respective sharp corners in the opposite edges of said two walls, said outer wall having its marginal edge projecting beyond the outer surface of said wall-forming strip and guarding and shielding the score line along which said tongues are united with said wall-forming strip.

3. A box comprising a bottom wall having two sharp notches in one edge formed with

sharp corners and having two sharp points on its opposite edge spaced apart the same distance as said sharp corners; a wall-forming strip having in its inner side score lines which are opposite said sharp corners when said strip is bent around the marginal portion of said bottom wall between said sharp corners, and having on its inner side a score line which is opposite one of said sharp points when said strip is bent around one side edge of said bottom wall, tongues projecting from one edge of said strip, said score lines guiding the positioning of said strip about said wall to prevent said strip from being placed in a position in which any of said tongues crosses said sharp corners of said notches or said sharp point and permitting said strip to be bent sharply into said sharp corners and around one of said sharp points; and means securing said tongues to one side of said wall.

4. A box comprising a bottom wall having two sharp notches in one edge formed with sharp corners and having two sharp points on its opposite edge spaced apart the same distance as said sharp corners; a wall-forming strip having in its inner side score lines which are opposite said sharp corners when said strip is bent around the marginal portion of said bottom wall between said sharp corners, and having on its inner side a score line which is opposite one of said sharp points when said strip is bent around one side edge of said bottom wall, tongues projecting from one edge of said strip, said score lines guiding the positioning of said strip about said wall to prevent said strip from being placed in a position in which any of said tongues crosses said sharp corners of said notches or said sharp point and permitting said strip to be bent sharply into said sharp corners and around one of said sharp points; means securing said tongues to one side of said wall; and an outer wall secured to the outer sides of said tongues and having sharp corners and sharp points in alinement with said first-named sharp corners and sharp points, said sharp corners in said outer wall being spaced apart the same distance as said sharp corners in said bottom wall and said sharp points being spaced apart the same distance as said sharp points on said bottom wall, and the marginal edge of said outer wall projecting laterally beyond and guarding the union of said strip and said tongues.

5. A box comprising a bottom wall having two sharp notches in one edge formed with sharp corners and having two sharp points on its opposite edge spaced apart the same distance as said sharp corners; a wall-forming strip having in its inner side score lines which are opposite said sharp corners when said strip is bent around the marginal portion of said bottom wall between said sharp corners, and having on its inner side a score line which is opposite one of said sharp points

when said strip is bent around one side edge of said bottom wall, tongues projecting from one edge of said strip, said score lines guiding the positioning of said strip about said wall to prevent said strip from being placed in a position in which any of said tongues crosses said sharp corners of said notches or said sharp point and permitting said strip to be bent sharply into said sharp corners and around one of said sharp points; means securing said tongues to one side of said wall; an outer wall having sharp corners and sharp points in alinement with said sharp corners and said sharp points on said bottom wall; and means other than the means which secures said tongues to the bottom wall securing said outer wall to said tongues in a relationship in which said sharp corners and said sharp points in and on said outer wall are in alinement with the sharp corners and sharp points in and on said bottom wall and in which the marginal edge of said outer wall projects beyond and guards the union of said strip and said tongues.

6. A box comprising a bottom wall having two sharp notches in one edge formed with sharp corners and having two sharp points on its opposite edge spaced apart approximately the same distance as said sharp corners; a wall-forming strip having thereon indicia which are opposite said sharp corners when said strip is bent around the marginal portion of said bottom wall between said sharp corners, and also having thereon a designated point which is opposite one of said sharp points when said strip is bent around one side edge of said bottom wall, tongues projecting from one edge of said strip, said indicia and said designated point guiding the positioning of said strip about said wall to prevent said strip from being placed in a position in which any of said tongues crosses said sharp corners of said notches or said sharp point, and permitting said strip to be bent sharply into said sharp corners and around one of said sharp points; and means securing said tongues to one side of said wall.
